UNITED STATES PATENT OFFICE.

CHARLES TRUE, OF SHERWOOD, OREGON.

HOP-SCOOP.

No. 823,007.

Specification of Letters Patent.

Patented June 12, 1906.

Application filed November 10, 1905. Serial No. 286,760.

To all whom it may concern:

Be it known that I, CHARLES TRUE, a citizen of the United States, residing at Sherwood, in the county of Washington and State 5 of Oregon, have invented certain new and useful Improvements in Hop - Scoops, of which the following is a specification.

The object of my invention is to provide an improved construction of scoop designed especially for use in hop-drying kilns and arranged to take dry hops off the kiln-floor after they have been dried thereon.

The invention consists, essentially, of an improved construction of scoop of this character which is provided with rollers on which it may travel over the floor of the kiln, so that it will not scrape over the floor-cloth, and consequently will not wear the same out. In addition the provision of the rollers enables 20 the workmen to operate the scoop quickly, thereby saving labor and expediting the work.

For a full description of the invention and the merits thereof and also to acquire a 25 knowledge of the details of construction of the means for effecting the result reference is to be had to the following description and accompanying drawings, in which—

Figure 1 is a front perspective view of the 30 scoop embodying my invention. Fig. 2 is a longitudinal sectional view thereof. Fig. 3 is a rear perspective view.

Corresponding and like parts are referred to in the following description and indicated 35 in all the views of the drawings by the same reference characters.

Referring to the drawings, the reference-numeral 1 indicates the body of the scoop, which comprises a framework consisting of a 40 rear transverse bar 2, two side bars 3, joined thereto at the ends and preferably braced by diagonal braces 4, a front scraper-bar 5, connected to the front ends of said side bars 3, and a longitudinal brace 6, extending from 45 the scraper-bar 5 to the rear bar 4 and preferably intermediate of said two bars, said brace 6 also serving for the support of the handle 7, which is secured to it at its lower end and extends upwardly and rearwardly there- 50 from.

In connection with the lower frame the body of the scoop embodies an upper diagonal frame consisting of an upper rear bar 2', two diagonal side bars 3', connected at their rear ends to the bar 2' and preferably braced, as shown at 4'. Said side bars 3' are also fastened at their front ends to the ends of the

side bars 3 and the scraper-bar 5. The scraper-bar 5 has a beveled edge 5'. A suitable covering 8, of canvas or other suitable textile material, is secured to the body of the 60 scoop, composed of the two frames above described, preferably by being tacked to the bars of the frame, as shown, and forming a textile bottom, sides, and rear end for the scoop, the front of the scoop being open. The 65 handle 7 extends upwardly and rearwardly, as above set forth, and is secured to the rear bar 2' at the point that intersects the same by any suitable fastening device, as indicated at 9. 10 designates two diagonal braces or 70 stays which run from the upper cross-bar 2' to the lower cross-bar 2. At the rear of the scoop there are mounted two brackets, each of which consists of two spaced-apart substantially vertically extending members 11, 75 of wood or the like, which are secured at their upper ends to the rear cross-bar 2' and at their lower ends to the lowermost cross-bar 2, whereby they serve as additional bracing means for holding the two frames rigid in re- 80 lation to each other, and at the lower end of each of the brackets there is journaled a horizontal roller 12, provided with suitable trunnions mounted to turn in the lower end of the bracket members 11. The rollers 12 have 85 their peripheries projecting below the lowermost cross-bar 2, so that the scoop is raised slightly off the floor of the kiln at its rear end when being operated, and thereby the floor is saved the injury which would otherwise 90 ensue from the abrasion of the scoop over the floor-cloth.

From the foregoing description, in connection with the accompanying drawings, it will be seen that I have provided a scoop of this 95 character which is exceedingly light and strong in construction, which may be conveniently manipulated over the floor of a kiln to scoop up the hops from the same, and which will enable the workmen to clean the 100 floor effectually of the hops without breaking or crushing them, leaving no hops on the floor for the feet of the workmen to crush, and insuring less waste than with the scoops of ordinary construction.

Having thus described the invention, what is claimed as new is—

1. A scoop, comprising lower and upper frames rigidly secured together, a textile covering for said frames, brackets at the rear of said frames and connecting the same whereby to brace them, and rollers mounted in

said brackets, as and for the purpose set forth.

2. A hop-scoop, comprising a lower frame, a diagonal frame secured to the lower frame 5 at its forward end, a textile covering secured to said frames whereby to constitute the body of the scoop, vertically-extending brackets connecting the rear ends of said frames and bracing the same, a roller mounted in each of 10 said brackets, and a handle secured at its forward end to the lower frame and extending upwardly and rearwardly and connected to the diagonal frame.

3. A device of the character described 15 comprising a lower frame embodying a rear cross-bar, two side bars connected and braced thereto, a front scraper-bar connected to the front ends of the side bars, and a longitudinal brace connecting the scraper-bar 20 with the rear cross-bar, a second frame em-

bodying an upper rear cross-bar, two diagonally-extending side bars connected and braced thereto, and attached at their forward ends to the front ends of the lower frame, diagonal braces connecting said two frames, a 25 textile covering for said frames, a handle secured to the longitudinal brace of the lower frame and also to the rear cross-bar of the other frame, brackets embodying two spaced-apart vertical members secured at their ends 30 to the rear cross-bars of the frames and bracing the latter, and rollers journaled in the lower ends of said brackets, as and for the purpose set forth.

In testimony whereof I affix my signature 35 in presence of two witnesses.

CHARLES TRUE. [L. s.]
